DESIGN FOR A CHAIR BACK

Viktor Schreckengost, Cleveland Heights, Ohio, assignor to The Murray-Ohio Manufacturing Company, Cleveland, Ohio, a corporation of Ohio

Application March 18, 1941, Serial No. 99,669

Term of patent 7 years

To whom it may concern:

Be it known that I, Viktor Schreckengost, a citizen of the United States, residing at Cleveland Heights, county of Cuyahoga and State of Ohio, have invented a new, original, and ornamental Design for a Chair Back, of which the following is a specification, reference being had to the accompanying drawing, forming a part thereof.

Fig. 1 is a front elevational view of the chair back, showing my design;

Fig. 2 is a side elevational view of the chair back;

Fig. 3 is a cross-sectional view of the chair back taken on the line 3—3 of Fig. 1;

Fig. 4 is a cross-sectional view of the chair back taken on the line 4—4 of Fig. 1;

Fig. 5 is a cross-sectional view of the chair back taken on the line 5—5 of Fig. 1;

Fig. 6 is a cross-sectional view of the chair back taken on the line 6—6 of Fig. 1.

I claim:

The ornamental design for a chair back, substantially as shown.

VIKTOR SCHRECKENGOST.
